CLAIM

The ornamental design for a table base, as shown and described.

DESCRIPTION

FIG. 1 is a perspective elevation view of the table base. (Broken lines are for illustrative purposes only and form no part of the claimed design.)

FIG. 2 is a front elevational view of the table base; rear elevational view is identical.

FIG. 3 is a right side elevational view of the table base; the left side elevational view is identical.

FIG. 4 is a top plan view of the table base.

FIG. 5 is a bottom plan view of the table base.

FIG. 6 is a perspective view showing a second embodiment of my new design which is similar to the first embodiment;

FIG. 7 is a perspective view showing a third embodiment of my new design which is similar to the first embodiment; and,

FIG. 8 is a perspective view showing a fourth embodiment of my new design which is similar to the first embodiment.
